UNITED STATES PATENT OFFICE.

GEORGE W. WACKER, OF RUTHERFORD, NEW JERSEY, ASSIGNOR TO NATIONAL CARBON COMPANY, INC., OF NEW YORK, N. Y., A CORPORATION OF NEW YORK.

PORTABLE ELECTRIC LIGHT.

1,312,220.

Specification of Letters Patent.

Patented Aug. 5, 1919.

Application filed March 7, 1918. Serial No. 220,890.

To all whom it may concern:

Be it known that I, GEORGE W. WACKER, a citizen of the United States, residing at Rutherford, county of Bergen, State of New Jersey, have invented certain new and useful Improvements in Portable Electric Lights, of which the following is a specification, reference being had therein to the accompanying drawings, forming part thereof.

10 My invention relates to self-contained or battery operated portable electric lights, and has for its object to effect improvements in the construction of lights of this type employing a tubular battery-containing casing which at its forward end has a removable lamp or a removable lamp-carrying reflector. The principal object of my invention is to provide for retaining the battery in the casing without any danger of short-circuiting when the lamp or the lamp-carrying reflector is removed. As an example of a portable electric light of a kind to which the improvements of my invention are applicable, reference may be had to the patent to Conrad Hubert, No. 1,220,634 of March 27, 1917, for portable electric light. Other objects of my invention are inexpensiveness of manufacture, simplicity of construction, durability, reliability, and other objects and advantages 30 which will hereinafter appear.

My invention includes various features of construction and combinations of parts, as will appear from the following description.

I shall now describe the portable electric light embodying my invention illustrated in the accompanying drawings and shall thereafter point out my invention in claims.

Figure 1 is a central longitudinal section with parts in elevation of a tubular portable electric light embodying my invention.

Fig. 2 is a similar view with the lamp-carrying reflector removed.

Fig. 3 is a central longitudinal section on a plane indicated by the line 3-3 of Fig. 2 as viewed from below with the battery and end cap both removed.

In the portable electric light embodying my invention illustrated in the accompanying drawings a distinguishing feature is a 50 battery-engaging hook 1 shown as of substantially semi-circular form and as projecting inwardly and rearwardly from the forward end of a sheet metal strip and as having a straight rearwardly extending shank part 2. Rearward from the hook 1

the shank 2 is shown as secured by means of a small tubular rivet-forming eyelet 3 to the inner side of a metallic circuit-completing contact strip 4, and at its lower end the shank 2 and contact strip 4 are both secured 60 by means of a longer rivet-forming eyelet 5 to the inner side of a tubular casing part 6 shown as formed of insulating material. Rearward from the rear end of the shank 2 of the hook 1 the metallic contact strip 4 is 65 rather sharply offset inwardly at 7 to provide a battery spacing part 8.

With the exception of the embodiment therein of the battery-engaging hook 1 and the inwardly offset battery spacing part 8, 70 the construction of the portable electric light illustrated in the drawings is substantially of a usual construction and is of substantially the same construction disclosed in the above mentioned patent to Conrad Hubert, No. 1,220,634 of March 27, 1917, for portable electric light. The remaining 75 co-operative parts of the portable electric light illustrated in the accompanying drawings will now be sufficiently described for the 80 clear understanding of my present invention which is embodied therein.

The contact strip 4 extends longitudinally within the casing tube 6, the rear end of this contact strip 4 is secured to the casing tube 85 6 by means of a rivet-forming eyelet 9, and the forward end of the contact strip 4, at the front of the battery-engaging hook 1, projects transversely inward at an outward inclination to form a contact-making resilient 90 end part 10. The free outer circuit-completing or contact-making end 10 of the contact strip 4 in the construction illustrated in the drawings is engaged by the inner side of a metallic circuit-completing contact disk 11 95 which is held in place upon and supported by a removable metallic reflector 12 by means of an inwardly and outwardly flanged metallic screw-threaded lamp socket 13, the contact disk 11 and lamp socket 13 100 being electrically insulated from the metallic reflector 12 by means of interposed insulation shown as an insulating disk 14 and an insulating ring or washer 15. This construction for electrically insulating the metallic contact disk 11 and metallic lamp socket 13 from the metallic reflector 12 forms the subject of the patent to Conrad Hubert, No. 1,157,395 of October 19, 1915, for portable electric light, and 110

is also disclosed in the hereinbefore mentioned patent to Conrad Hubert, No. 1,220,634 of March 27, 1917, for portable electric light.

- 5 At its outer end the removable metallic reflector 12 is provided with a slight peripheral flange which rests upon an inwardly turned annular flange formed on a usual screw-threaded end band 16 shown as
 10 secured upon the outer end of the non-conducting casing tube 6 by means of rivet-forming eyelets 17, one of which appears in the drawings. The removable reflector 12 is held in place upon the casing tube 6 by
 15 means of an end glass shown as a usual lens 18, and the lens 18 is held in place by means of a usual end ring 19 screwed over the end band 16. A usual miniature incandescent lamp has its terminal-forming base 20
 20 screwed into the lamp socket 13 so that its central terminal 21 will be exposed at the inside of the casing, and its bulb 22 will be exposed outwardly within the reflector 12. The inner or rear end of the casing tube
 25 6 is closed by means of a usual end cap 23 screwed over an end ring 24 which is held in place upon the casing tube 6 by means of rivet-forming eyelets 25, one of which appears in the drawings. A battery-sup-
 30 porting coiled thrust spring 26 is carried by the end cap 23 at the inside thereof. A usual dry battery is contained within the battery-containing and lamp-carrying casing including the tubular non-conductive
 35 casing part 6, and this battery is shown as comprising two battery cells contained within a usual paper insulating tube 27, and having zinc terminal-forming cups 28 and central carbon terminals 29. The exposed
 40 central terminal 29 at the outer end of the battery is pressed against the central terminal 21 of the lamp by the battery-supporting thrust spring 26 which engages the rear end of the rearmost zinc cup 28, which forms
 45 the other terminal of the battery.

A metallic circuit-completing strip 30 extends forward within the casing tube 6 from the rear end ring 24 to a point adjacent to and shown in Fig. 3 as laterally spaced
 50 from the rear end of the contact strip 4, and this circuit-completing strip 30 is adapted to be electrically connected to the contact strip 4 by any suitable circuit-controlling means, and the circuit controller shown in
 55 the drawings and now to be briefly described is substantially the same as that disclosed in and forming the subject of the hereinbefore mentioned patent to Conrad Hubert, No. 1,220,634 of March 27, 1917, for portable
 60 electric light. A metallic contact box 31 is held in place upon the outer side of the non-conductive tubular casing part 6 by means of a pair of similar rivet-forming eyelets 32 and 33 of which the eyelet 33 also holds in
 65 place the forward end of the circuit-com-

pleting strip 30, as appears in Fig. 3. The contact box 31 has therein a contact spring 34 secured in place at one end thereof by means of a rivet 35 and at its other end provided with a push button 36 projecting at 70 its outer rounded end to the outside of the contact box 31, and at its inner end adapted to be brought into circuit-closing engagement with the outer end of a contact prong 37, shown as formed on the contact strip 4, 75 and projecting through an opening 38 to the outside of the casing tube 6 within the contact box 31. The push button 36 is also adapted to be operated by means of a slide 39 mounted upon the contact box 31. 80

It is to be noted that when the central terminal 29 of the forward battery cell is in contact with the central terminal 21 of the lamp, by reason of the forward thrust of the battery-supporting spring 26, the upper end 85 of the outer battery cell is spaced backward from and out of contact with the adjacent end of the inwardly and rearwardly turned battery-engaging hook 1, thereby assuring circuit-completing connection with the central terminal 21 of the lamp, as will be readily understood. However, should the forward end ring 19 be removed for any purpose, for example, for renewing the lamp, which in the construction illustrated in the 90 drawings is accomplished by removing the removable lamp-carrying reflector 12, then the battery will be pushed forward by the thrust spring 26 until the forward end of the outer battery cell is engaged by the hook 100 1, the rearwardly turned end of which comes into contact with the usual insulating material 40, which is commonly ordinary sealing wax, contained within the outer end of the zinc cup 28 and surrounding the outer 105 projecting end of the carbon electrode rod 29. The material of which the hook 1 is formed is sufficiently rigid thus to hold the battery against the thrust of the coiled spring 26, but the material forming the contact strip 4 is more flexible so that the inwardly projecting contact-making end part 10 thereof is adapted to make a reslient contact with the hereinbefore mentioned contact disk 11, under the pressure of which 110 it is adapted to yield slightly inward, as will be clear from a comparison of Figs. 1 and 2.

The engagement of the end of the hook 1 with the insulating material 40 of the forward battery cell prevents the outer edge of the zinc cup 28 from being pushed into contact with the inwardly projecting contact-making end 10 of the contact strip 4 by the thrust spring 26, it having been found in 120 practice that the upper edge of the cell-containing paper tube or carton 27 usually will not offer any substantial protection in this respect, and if the edge of the zinc cup 28 were to come into contact with the con- 125

130

tact-making end part 10 then the battery, or at least the rear cell thereof would be short-circuited through the connections hereinbefore described. Also in a construction in which the contact-making end part 10 of the contact strip 4 is omitted, the battery-engaging hook 1 will prevent the battery from dropping out of the forward end of the casing tube 6 when the lamp-carrying reflector 12 is removed and will accomplish this result without producing a short-circuit of the battery.

It has been found in practice that the ends or edges of the paper carton tube 27 often become more or less mutilated so as to expose more or less of the ends of the terminal-forming zinc cups 28 of the battery. However, ordinarily this mutilation will extend in only a comparatively short distance from the ends or edges of the paper tube 27. In such cases of the mutilation of the paper tube 27 it has been found in practice that not only will a short-circuit of the battery be produced when the lamp-carrying reflector is removed, as above described, but that also the upper exposed side part of the forward zinc battery cup 28 is liable to come into circuit-completing contact with the adjacent side of a usual metallic contact strip, such for example as the contact strip 4, and thereby produce a short-circuit of the battery even while the lamp-carrying reflector 12 and lamp are in place. In order to prevent the possibility of such a short-circuit being formed I have provided the hereinbefore described inwardly offset part 8 upon the contact strip 4 which engages the side of the paper tube 27 at a point some distance inward from the outer end thereof, and inward beyond where any usual mutilation of the paper tube 27 at its upper edge would extend. This inwardly offset battery-spacing part 8 of the contact strip 4 therefore will effectually prevent the contact of the side of the zinc cup 28 with an adjacent metallic part, for example, in the construction illustrated in the drawings with the adjacent inner surface of the shank 2 of the battery-engaging hook 1 or with the rivet-forming eyelets 3 and 5 should the adjacent upper end part of the paper tube 27 be mutilated or torn away so as to expose the outer surface of the zinc battery cup 28.

It is obvious that various modifications may be made in the construction shown in the drawings and above particularly described within the principle and scope of my invention.

I claim:

1. A portable electric light having, in combination, a battery-containing and lamp-carrying casing, and a circuit completing contact strip mounted on the casing at the inside thereof and provided with means engageable with the forward end of the bat-

tery and also with means engageable with the side of the battery inward from the forward end thereof, both of such means being adapted to prevent the electrical connection of the upper part of the zinc battery cup 70 with said circuit-completing contact strip.

2. A portable electric light having, in combination, a battery-containing and lamp-carrying casing part, and a circuit-completing contact strip at the inside of said casing part and provided with an inwardly turned part engageable with the forward end of the battery inward from the zinc cup thereof for limiting the forward movement of the battery and adapted to prevent the 80 contact of the upper part of the zinc cup with said circuit-completing contact strip.

3. A portable electric light having, in combination, a battery-containing and lamp-carrying casing part, and a circuit-completing contact strip carried by said casing part at the inside thereof and turned inward at its forward contact-making end, said contact strip also being provided with an inwardly projecting part adapted to engage with the forward end of the battery inward from the zinc cup thereof for thereby preventing the contact of the upper edge of the zinc cup with the inwardly turned contact-making end of said circuit-completing contact strip.

4. The invention claimed in claim 3 in which said circuit-completing contact strip is further provided inward from the outer end of the battery with a laterally projecting part engageable with the side of the battery for preventing the contact of the upper part of the zinc cup with the adjacent part of said contact strip.

5. A portable electric light having, in combination, a tubular battery-containing and lamp-carrying casing adapted to support a miniature incandescent lamp with its central terminal exposed within the casing at the forward end thereof, a battery-supporting spring at the rear end of the casing adapted to push the battery forward with its central terminal in contact with the central terminal of the lamp, and a circuit-completing contact strip carried by said tubular casing at the inside thereof and having at its forward end an inwardly turned contact-making end part, said contact strip being provided with an inwardly extending part at the front of the forward end of the battery and normally out of contact therewith but adapted when the lamp is removed to engage the forward end of the battery inward from the zinc cup thereof.

6. The invention claimed in claim 5 in 125 which said circuit-completing contact strip is further provided with a projecting part for engaging the side of the battery inward from the outer end thereof.

7. A portable electric light having, in 130

combination, a tubular casing part, a removable lamp-carrying reflector at the forward end of said casing part and arranged to expose the central terminal of the lamp
5 at the inside of said casing part, a closure for the rear end of said casing part, a battery-supporting thrust spring acting between said closure and the rear end of a battery for maintaining the central terminal
10 of the battery in contact with the central terminal of the lamp, and a circuit-completing contact strip within said tubular casing part provided at its forward end with an inwardly turned hook normally out of contact with the forward end of the battery but adapted when the said lamp-carrying reflector is removed to engage with the insulating material of the forward end of the battery inward from the upper edge of the
15 zinc cup thereof for thereby limiting the forward movement of the battery without making contact with said zinc cup.
8. The invention claimed in claim 7 in which said contact strip is offset inwardly
20 rearward from the hook and from the forward edge of the battery for thereby spacing the upper end of the battery from the adjacent part of said contact strip.
9. The invention claimed in claim 7 in
25 which said circuit-completing contact strip is further provided outwardly from said battery-engaging hook with an inwardly projecting contact-making end part.

10. The invention claimed in claim 8 in which said circuit-completing contact strip 35 is further provided outwardly from said battery-engaging hook with an inwardly projecting contact-making end part.

11. A portable electric light having, in combination, a tubular casing part of insulating material, and a circuit-completing contact strip extending longitudinally within and secured to said casing tube and provided with an inwardly projecting part normally out of contact with but adapted to engage with the insulating material of the forward end of the battery for limiting the forward movement of the battery in the casing tube.

12. The invention claimed in claim 11 in 50 which said circuit-completing contact strip is provided with an inwardly projecting contact-making end forwardly from said battery-engaging part.

13. The invention claimed in claim 12 in 55 which said inwardly projecting battery-engaging part is in the form of a hook.

14. The invention claimed in claim 13 in which said hook-forming part is a separate piece of metal secured to said circuit-completing part, the battery-engaging hook being comparatively rigid and the contact-making end part being more flexible.

In testimony whereof I have affixed my signature to this specification.

GEORGE W. WACKER.
